UNITED STATES PATENT OFFICE.

GARDINER S. BOWDEN, OF BROOKLYN, NEW YORK, ASSIGNOR TO J. B. BOWDEN & CO.,
A COPARTNERSHIP COMPOSED OF MARTIN L. BOWDEN AND GARDINER S. BOWDEN,
OF NEW YORK, N. Y.

DESIGN FOR A WEDDING RING.

Application filed August 26, 1925. Serial No. 14,590. Term of patent 14 years.

To all whom it may concern:

Be it known that I, GARDINER S. BOWDEN, a citizen of the United States, and resident of the borough of Brooklyn, in the city and State of New York, have invented a new, original, and ornamental Design for a Wedding Ring, of which the following is a specification, reference being had to the accompanying drawing, forming part thereof.

The figure is a perspective view of my new design for a ring.

I claim:

The ornamental design for a wedding ring substantially as shown.

GARDINER S. BOWDEN.
